UNITED STATES PATENT OFFICE

ISAAC ANDREWS, OF SPARTANBURG, SOUTH CAROLINA

LOOM REED CONSTRUCTION

Application filed January 26, 1931. Serial No. 511,383.

This invention relates to loom reed construction, and more particularly to reeds designed for weaving coarse material.

For the sake of illustration, it might be stated that considerable difficulty is experienced in securing the ends of the dents of coarse reeds together by the soldering method, due to the fact that the dents are spaced such great distances apart, the solder falls therefrom before it hardens.

It is therefore the object of the present invention, to provide a coarse reed so constructed that the solder will be held in position between the dents until it hardens, whereupon the dents are securely held together by the solder.

With the foregoing and other objects in view, which will appear as the description proceeds, the invention resides in the combination and arrangements of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a fragmental elevational view of a loom reed constructed in accordance with the invention, one of the caps being shown in section.

Figure 2 is a longitudinal sectional view through the reed.

Figure 3 is an enlarged fragmental elevational view illustrating one end of the reed, a portion of the backing member being broken away.

Figure 4 is a vertical fragmental sectional view through the reed.

Referring to the drawing in detail, the reference character 5 designates the dents of the reed, and as shown, these dents are substantially large and spaced appreciable distances apart, the construction of the reed being especially designed for coarse weaving.

At the sides of the reed, are bars 6, to which the ribs 7 are secured, the ribs 7 being disposed on opposite sides of the reed and spaced appreciable distances from the ends of

the dents, as clearly shown by Figure 1 of the drawing.

Wrapped around the ribs 7, is a cotton binding member 8 which acts as a cushioning means between the dents, to cushion the movements of the dents, with respect to the ribs 7. The solder which is used in binding the extended ends of the dents 5 together, is indicated by the reference character 9, and is held in position by means of the caps 10 that extend throughout the length of the reed, at the upper and lower ends of the reed.

As clearly shown by Figure 2 of the drawing, the caps comprise side flanges 11 and 12 respectively, the flanges 12 being slightly taller than the flanges 11, so that the reed may be tilted slightly during the dipping, to permit the solder to flow into the spaces between the dents.

The backing of the reed, which is indicated by the reference character 15, is hollow or tubular in formation, the same being provided with an offset portion 16 of a width to receive the caps 10, to the end that any possibility of the backing twisting, will be absolutely eliminated, thereby holding the reed in perfect alignment while in the loom.

After the solder has been positioned between the dents, the tubular backing members 15 are positioned by sliding them over the ends of the dents, one end of each backing member being open to permit the positioning of the backing members in this way.

After the backing members have been properly positioned, the open ends of the backing members are closed by means of the caps 17, which are soldered in position.

Due to this construction, it will be seen that these caps 17 may be readily removed to permit of the repairing of the reed, with facility, without sacrificing the rigidity of the reed.

I claim:

1. In a loom reed, dents, ribs disposed on opposite sides of the dents, cushioning means between the dents for restricting lateral movement of the dents, elongated caps having parallel flanges, embracing the side edges of the dents near the ends thereof and providing pockets, solder disposed within the

2
pockets for securing the dents together, and backing members positioned over the caps.

2. In a loom reed, dents, transversely disposed ribs secured to the dents on the opposite sides of the dents, said ribs being disposed in spaced relation with the ends of the dents, cushioning means on the ribs and held between the dents, caps fitted over the ends of the dents, said caps having side flanges 10 closely engaging the edges of the dents and providing pockets at the ends of the dents, solder positioned within the pockets for securing the dents in spaced relation, and backing strips positioned over the caps.

15 3. In a loom reed, dents, ribs disposed on opposite sides of the dents and in parallel relation with respect to each other, said ribs being disposed in spaced relation with the lower ends of the dents, cushioning means 20 positioned around the ribs and disposed between the dents to hold the dents in lateral spaced relation with respect to each other, said cushioning means being spaced from the ends of the dents, caps fitted over the ends of the dents for holding the dents in alignment and providing pockets between the dents, solder disposed in the pockets, and backing members positioned over the caps.

25 4. A loom reed comprising dents arranged in parallel spaced relation with each other, elongated caps in which the ends of the dents are positioned, means for holding the dents in spaced relation with each other, solder disposed between the dents at the ends thereof for securing the ends of the dents together, a tubular backing strip positioned at each end of the reed, each backing strip having an offset portion accommodating the ends of the dents, and the free edges of the tubular 30 backing strips contacting with the side edges of the dents at points in spaced relation with the ends of the dents.

45 In testimony that I claim the foregoing as my own, I have hereto affixed my signature.

ISAAC ANDREWS.
